UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER-MOTION FOR LOOMS.

1,327,070.

Specification of Letters Patent.

Patented Jan. 6, 1920.

Application filed September 19, 1917. Serial No. 192,187.

To all whom it may concern:

Be it known that I, EDWARD S. STIMPSON, a citizen of the United States, residing at Hopedale, in the county of Worcester and 5 State of Massachusetts, have invented an Improvement in Feeler-Motions for Looms, of which the following description, in connection with the accompanying drawings, is a specification, like characters on the drawings representing like parts.

This invention relates to feeler motions for looms, and more particularly to that type of feeler motions wherein the change in the operative condition of the loom, such 15 as replenishment of filling, is effected prior to complete exhaustion of the filling in the shuttle.

Where replenishment of filling is to be made before the filling in the shuttle is 20 entirely exhausted, it is essential that the feeler motion be sensitive either to the presence or absence of a working supply of filling in the shuttle. Should it indicate substantial exhaustion when there still remains 25 in the shuttle a sufficient working supply, much waste is liable to occur; while, on the other hand, should it fail to indicate substantial exhaustion until the filling is entirely withdrawn, a defect in the cloth is 30 liable to result. In this general type of feeler motion, some filling usually remains on the old filling carrier when it is ejected and replaced by a fresh supply, and minimum waste with maximum perfect cloth 35 production dictate that the amount of filling remaining on the ejected carrier should not only be small but substantially uniform in amount.

In the patent to Edward S. Stimpson No. 40 1,309,226 dated July 8, 1919, there is shown, described and broadly claimed a feeler motion wherein the feeler member is supported in a position for movement inclined to the longitudinal axis of the shuttle or filling 45 carrier and is held from movement longitudinally along the filling carrier by the filling on a detecting beat until the filling is substantially exhausted, and is then moved along the filling carrier under the 50 frontward push to initiate filling replenishment. In the present invention the feeler member is supported in an inclined position relative to the longitudinal axis of the shuttle or path of lay movement, but instead 55 of effecting replenishment of filling through

means actuated by the sidewise or lateral movement of the feeler member when the filling is substantially exhausted, as in the patent mentioned, the present invention provides means which is actuated by the front- 60 ward movement of the feeler member when it has been displaced laterally by the frontward pressure of the substantially denuded filling carrier.

In carrying the present invention into 65 practical effect, the controller for controlling the train of mechanism for effecting replenishment of filling is provided with a finger which, on each detecting beat when a working supply of filling is present in the 70 shuttle, fails to be hit by a part carried by the feeler member as the latter moves frontwardly, but which is struck by a part carried by the feeler member when the latter moves frontwardly following an indication of substantial 75 exhaustion of filling.

The above characteristics of the invention and other important and novel features thereof will be hereinafter described in connection with the accompanying drawings 80 showing one good form thereof, and the novel features and combinations will then be definitely set forth by the claims.

In the drawings:—

Figure 1 is a perspective view of a portion of a loom provided with the present invention, some of the parts being broken away for clearness of illustration.

Fig. 2 is a detail plan view on a larger scale showing the improved feeler mechanism and its operation when a working supply of filling is in the shuttle.

Fig. 3 is a view similar to that of Fig. 2 showing the relation of parts when the filling in the shuttle is substantially exhausted 95 on a detecting beat.

Fig. 4 is a detached detail showing one form of means for transmitting the indicating movement of the feeler to the train of mechanism to be actuated when the filling 100 is substantially exhausted on a detecting beat.

Referring to the drawings, the loom frame 1, only a portion of which is shown in the drawings may be of any suitable 105 character for supporting the operating parts. Mounted on the loom is the transverse or rock shaft 2 (Fig. 1) supported by the bearings 3 which may be secured to the loom frame as by means of the bolts 4. Se- 110

cured to rock with the transverse or rock shaft 2 is the upwardly extending arm 5 (Fig. 1), to the upper portion of which is pivoted at 6 the arm 7, which for identification 5 may hereinafter be termed the actuator, because by engagement of the rearwardly extending end 8 with an operating member 9, operation of the filling replenishing mechanism is effected. The operating member 9 may be any suitable part of the loom elements, such, for example, as weft hammer or cam follower, or it may be a part secured for operation in unison therewith, as well understood by those skilled in the 10 art. The operating member has an upper engaging portion 10, which, when the actuator 7 is lifted, as will hereinafter more fully appear, engages the rearwardly extending end portion 8 of the actuator to move it frontwardly and rock the transverse or rock shaft 2.

The lay carries the usual shuttle-box, and inasmuch as the feeler member of the present invention is to feel for the filling in the 25 shuttle on a detecting beat, the front wall 11 of the shuttle-box is provided with a slot or opening 12, and similarly the front wall 13 of the shuttle (Figs. 1, 2 and 3) is provided with an opening 14 adapted to register with 30 the opening 12 in the shuttle-box when the shuttle containing the filling carrier 15 is properly boxed on the detecting side of the loom.

The loom frame 1 has the usual shipper 35 stand 16 provided with the slot 17 through which extends the shipper 18.

The present invention contemplates that the feeler member shall be supported in position to enter the shuttle at an inclination 40 to the longitudinal axis of the shuttle or filling carrier, and that on the forward movement of the lay the feeler member may be moved frontwardly in an inclined direction to the lay movement. Various forms of supports may be employed for the accomplishment 45 of this purpose, but in the present instance of the invention, the loom frame or shipper stand has projecting therefrom a supporting plate or bracket 19 upon which 50 is secured the feeler stand 20. In the present instance of the invention, the feeler stand 20 is provided with a slot 21, through which extends the securing bolt 22, the construction being such, that the feeler stand may 55 be adjusted on the supporting plate or bracket 19.

Rising from the rear portion of the feeler stand 20 is the bearing 23 having a slot 24 in which rests the feeler member 25 which 60 may be suitably confined for movement in the slot 24 by means of a cap piece 27 overlying the feeler member 25 and secured in position by suitable screws or other means 65. The feeler stand is provided at its front portion with the bearing 29 for the front

end portion of the feeler member 25. In the present instance of the invention, the bearing 29 is formed of a part separate from the feeler stand and secured thereto in desired position by means such as the bolt 30. The bearing 29 has an opening 31 therein of somewhat larger dimensions than the feeler member 25, as more fully shown in Figs. 2 and 3, through which the front end portion of the feeler member 25 extends, the construction being such that as the feeler member 25 is moved frontwardly in an inclined direction on a detecting beat, the enlarged opening 31 in the bearing 29 will permit the feeler member to swing or move laterally.

The feeler stand 20 is provided with a frontwardly inclined slotted portion 32 which is bridged by a part 33 secured to the feeler member 25 between the front and rear bearings of the feeler stand, the side portions of the part 33 preferably riding upon the feeler stand 20 at each side of the slot 32 when the feeler member 25 is moved frontwardly in its inclined path, as will more fully appear.

The feeler member 25 is normally under the influence of means tending to move it rearwardly, and in the present instance of the invention, such means consists of a spring 34 surrounding the feeler member 25 and having one end portion resting against the bearing 29, and the other end portion against the part 33, the construction being such, that the spring 34 normally acts upon the feeler in the direction of its inclination to the longitudinal axis of the shuttle or filling carrier.

The feeler member 25 has an end portion 35 which is suitably roughened or toothed to engage the filling or filling carrier on a detecting beat, the construction being such, that should a working supply of filling be present in the shuttle as indicated in Fig. 2 on a detecting beat, the end 35 of the feeler member will be held by the filling from movement along or longitudinally of the filling carrier under the frontward impulse imparted to the feeler member thereby, but should the filling be substantially exhausted, though not quite depleted, the frontward push of the filling carrier upon the end 35 of the feeler member will cause the feeler member to move along or in a direction longitudinally of the filling carrier or shuttle as the lay makes its detecting beat.

From the construction described, it will be apparent that when there is a working supply of filling present in the shuttle on a detecting beat, the feeler member will be moved frontwardly in an inclined direction, and its angular relation to the longitudinal axis of the shuttle or filling carrier will change during its frontward movement, as indicated by dotted and full lines (Fig. 2), the effect being that the control of the filling

upon the feeler member under the forward push will also change and the feeler be rendered more sensitive to the quantity of filling in the shuttle. When the filling has been 5 come substantially exhausted as indicated in Fig. 3, the end 35 of the feeler member will again engage the surface of the filling carrier or the few turns of filling yet remaining opposed to the end of the feeler member, 10 and the forward push will cause the feeler member to move in a direction longitudinally of the shuttle and assume a more acute angular relation with the longitudinal axis of the shuttle or filling carrier as the lay 15 completes its forward beat.

Connected to the feeler member 25 is a part 36, which, when the feeler is moved longitudinally of the filling carrier on a detecting beat, is positioned for engagement 20 with means for initiating filling replenishment. In the present instance of the invention, the part 36 is formed as a portion of the part 33 secured to the feeler member.

Mounted for rocking movement in suitable bearings 37 carried by the bracket 38 secured to the loom frame or shipper stand, is a rocker or controller 39 having a downwardly extended portion 40 adapted to be moved and cause rocking movement of the rocker or controller when the feeler member 25 has been moved longitudinally of the shuttle on a detecting beat, or in other words, when the filling is substantially exhausted. In the present instance of the invention, the 35 part 40 is formed as a finger secured to the rocker or controller 39 by a set screw 41, and suitable collars 42 restrain longitudinal movement of the rocker or controller 39. The rocker or controller 39 has a lifting 40 finger or crank arm 43, the end 44 of which extends under the actuator 7, the construction being such, that should the part 36 connected to the feeler member 25 contact with the down-turned portion 40 of the rocker or 45 controller as the feeler member moves forwardly in its inclined path on a detecting beat, the actuator 7 will be positioned for engagement by the operating member 9 to initiate filling replenishment.

From the construction described, it will be noted that the part 36 for rocking the rocker or controller 39 moves in an inclined path toward the front of the loom on a detecting beat, and that the rocker or controller 39 is supported for rocking movement about an axis at an angle to the path of inclined frontward movement of the part 36. It is, therefore, desirable that means be provided between the part 36 and the portion 40 of the rocker or controller to prevent disengagement of the part 36 from the part 40 of the controller as the former moves forwardly in its inclined path. To this end the feeler stand 20 has rising therefrom 55 a lug or support 45, and pivotally supported

on the lug 45 as at 46 is a transmitter 47 adapted to swing in a plane substantially parallel to the path of movement of the part 36 as the lay moves forwardly on a detecting beat when the filling is substantially exhausted. The transmitter 47 has a lateral extension 48 interposed between the down-turned portion 40 of the rocker or actuator 39 and the part 36 of the feeler member, the construction being such, that when, on a detecting beat with filling substantially exhausted, the part 36 has been moved laterally with the feeler member to engage the extension 48 of the transmitter 47, it will swing the transmitter and perforate turn the 80 rocker or controller to initiate filling replenishment.

On each detecting beat the feeler member 25 will be moved forwardly in a changing angular relation to the longitudinal axis of the shuttle by the forward push, and in order to return the feeler to its proper inclined feeling position when the lay goes back, the feeler stand is provided with a cam portion 49 which is adapted to be engaged by a downwardly extending lug 50 of the bridge part 33 as the spring 34 moves the feeler rearwardly. When the feeler is in its proper inclined feeling position, the bridge part 33 acts as a stop by contact with the rear bearing of the feeler stand, and in connection with the cam 49 maintains the feeler in proper feeling position.

In order that the sensitive character of the feeler may be maintained, notwithstanding the different kinds of filling employed, the present invention contemplates that the initial inclination of the feeler with respect to the longitudinal axis of the shuttle or filling carrier may be adjusted to suit the 105 conditions of use. To this end the plate or bracket 19 on which the feeler stand 20 is supported, is provided with a forwardly expanding recess 51 in which extends a rib 52 projecting from the under side of the 110 feeler stand 20, the construction being such, that by properly loosening the bolt 22, the inclination of the feeler with respect to the longitudinal axis of the shuttle may be changed at will. In order to gage or accurately determine the adjusted position of the feeler in its inclined relation with respect to the longitudinal axis of the shuttle, a scale 115 and pointer are provided. In the present instance of the invention, the pointer 53 is secured to the plate or bracket 19 and has an end portion overlying a graduated scale 54 secured to a front portion of the feeler stand, the construction being such that when the feeler is angularly adjusted, as hereinbefore 120 described, the amount of adjustment for the different kinds or character of filling in use 125 may be readily determined.

Claims.

1. In a feeler motion for looms, the com- 130

bination of a feeler member supported in a position inclined to the longitudinal axis of the shuttle and movable frontwardly on its support in changing angular relation to the longitudinal axis of the shuttle by the frontward push, said feeler member having an end to engage the filling and be held from movement longitudinally of the shuttle by the frontward push until the filling is substantially exhausted, a train of mechanism for effecting replenishment of filling including a rock-shaft, and a finger extending from the rock-shaft and adapted to be actuated by the frontwardly inclined movement of the feeler member on its support when the filling is substantially exhausted.

2. A feeler motion for looms, comprising, in combination, a feeler member, means for supporting the feeler member in an inclined position relative to the shuttle and for frontward and swinging movements about a changing fulcrum on each detecting beat, an end on the feeler adapted to engage and be held by the filling from movement along the filling carrier until substantial exhaustion of filling, a transmitter movable in a path inclined to the longitudinal axis of the shuttle and means actuated by the transmitter when moved by the feeler member for effecting a change of filling.

3. A feeler motion for looms, comprising, in combination, a feeler member supported in an inclined position relative to the longitudinal axis of the shuttle and for lengthwise and lateral movements on each detecting beat, an end on the feeler member for limiting the lateral movement of the feeler by engagement with the filling on a detecting beat and permitting the feeler to be displaced laterally an increased amount by the frontward pressure when the filling is substantially exhausted, a projection carried by the feeler member, a transmitter adapted to be moved in a path inclined to the longitudinal axis of the shuttle by the projection when filling is substantially exhausted, and a train of mechanism actuated by the transmitter for effecting replenishment of filling.

4. A feeler motion for looms, comprising, in combination, a feeler member supported in an inclined position relative to the longitudinal axis of the shuttle and for lengthwise and lateral movement on each detecting beat, means for adjusting the initial incli-

nation of the feeler member and shuttle, an end on the feeler member for limiting the lateral movement of the feeler by engagement with the filling on a detecting beat and permitting the feeler to be displaced laterally an increased amount when the filling is substantially exhausted, a transmitter, a train of mechanism for effecting replenishment of filling, and a finger interposed between the transmitter and train of mechanism.

5. A feeler motion for looms, comprising, in combination, a feeler member having a connected part movable frontwardly in a path inclined to the longitudinal axis of the shuttle on each detecting beat and having an end portion to engage and be held from movement along the filling carrier by the filling until substantial exhaustion of filling, a controller movable in a path inclined to the path of the part connected to the feeler, and a transmitter between the part carried by the feeler and the controller for moving the latter in its prescribed path through movement of the former in its different path.

6. In a feeler motion for looms the combination of a feeler stand, a feeler member mounted on said stand in an inclined position and for movement lengthwise in a direction inclined to the longitudinal axis of the shuttle, a swinging transmitter adapted to be moved by the feeler member in a direction inclined to the longitudinal axis of the shuttle when the filling is substantially exhausted, and means actuated by movement of the transmitter for effecting replenishment of filling.

7. A feeler motion comprising a feeler member mounted in an inclined position relative to the lay movement and movable lengthwise in a direction inclined to the lay movement on a detecting beat, a transmitter mounted independently of the feeler member and adapted to be actuated thereby as it moves frontwardly when the filling is substantially exhausted, a finger in the path of movement of the transmitter, and means actuated by the finger when moved by the transmitter to effect replenishment of filling.

In testimony whereof, I have signed my name to this specification.

EDWARD S. STIMPSON.
